Primary Examiner — Catherine Tuttle(74) *Attorney, Agent, or Firm* — Karen E. Klumas(57) **CLAIM**

The ornamental design for a bottle, as shown and described.

DESCRIPTION

FIG. 1 is a perspective view from above and one side;

FIG. 2 is a front elevational view;

FIG. 3 is a rear elevational view;

FIG. 4 is a side elevational view;

FIG. 5 is an elevational view of the other side;

FIG. 6 is a top plan view; and,

FIG. 7 is an underneath plan view.

The broken lines shown in FIG. 7 are included for the purpose of illustrating a portion of the bottle that forms no part of the claimed design.

1 Claim, 5 Drawing Sheets(56)
